(57) **CLAIM**

The ornamental design for a hinge for building, as shown and described.

DESCRIPTION

FIG. 1 is a perspective view of a hinge for building embodying my new design;

FIG. 2 is a top plan view of the hinge for building of FIG. 1; FIG. 3 is a bottom plan view of the hinge for building of FIG. 1;

FIG. 4 is a right side elevation view of the hinge for building of FIG. 1;

FIG. 5 is a left side elevation view of the hinge for building of FIG. 1;

FIG. 6 is a front elevation view of the hinge for building of FIG. 1;

FIG. 7 is a rear elevation view of the hinge for building of FIG. 1;

FIG. 8 is a cross-sectional view of the hinge for building through line 8-8 shown in FIG. 2; and

FIG. 9 is a cross-sectional view of the hinge for building through line 9-9 shown in FIG. 2.

FIG. 10 is a cross-sectional view of the hinge for building through line 10-10 shown in FIG. 2;

FIG. 11 is a cross-sectional view of the hinge for building through line 11-11 shown in FIG. 2; and,

FIG. 12 is a cross-sectional view of the hinge for building through line 12-12 shown in FIG. 2.

The broken lines shown in the figures represent portions of the hinge for the building that form no part of the claimed design.

The dot-dash lines are unclaimed boundary lines to denote the boundary of the claimed part and the unclaimed part.
